Primary Examiner — R. Johnson(74) Attorney, Agent, or Firm — Jose Cherson Weissbrot(57) CLAIM

The ornamental design for a glass cabinet, as shown and described.

DESCRIPTION

FIG. 1 is a front perspective view of a glass cabinet, showing the first embodiment of my new design;

FIG. 2 is a rear perspective view thereof;

FIG. 3 is a front elevation view thereof;

FIG. 4 is a rear elevation view thereof;

FIG. 5 is a left side elevation view thereof, the right side elevation view being a mirror image of FIG. 5;

FIG. 6 is a top plan view thereof;

FIG. 7 is a partial enlarged view of FIG. 1;

FIG. 8 is a partial enlarged view of FIG. 2;

FIG. 9 is a partial enlarged view of FIG. 3;

FIG. 10 is a front perspective view of a glass cabinet, showing the second embodiment of my new design;

FIG. 11 is a rear perspective view thereof;

FIG. 12 is a front elevation view thereof;

FIG. 13 is a rear elevation view thereof;

FIG. 14 is a left side elevational view thereof, the right side elevation view being a minor image of FIG. 14; and,

FIG. 15 is a top plan view thereof.

The broken lines in the figures depict portions of the glass cabinet, that form no part of the claimed design.

1 Claim, 13 Drawing Sheets(56)
